(57) **CLAIM**

The ornamental design for a grommet, as shown and described.

DESCRIPTION

FIG. 1 is a perspective view of a first embodiment of the grommet of the invention;

FIG. 2 is a top plan view of the grommet of FIG. 1;
FIG. 3 is a bottom plan view of the grommet of FIG. 1;
FIG. 4 is a first end elevation view of the grommet of FIG. 1;
FIG. 5 is a second end elevation view of the grommet of FIG. 1;
FIG. 6 is a side elevation view of the grommet of FIG. 1, the other side being a mirror image;
FIG. 7 is a perspective view of a second embodiment of the invention;
FIG. 8 is a top plan view of the grommet of FIG. 7;
FIG. 9 is a bottom plan view of the grommet of FIG. 7;
FIG. 10 is a first end elevation view of the grommet of FIG. 7;
FIG. 11 is a second end elevation view of the grommet of FIG. 7;
FIG. 12 is a side elevation view of the grommet of FIG. 7, the other side being a mirror image;
FIG. 13 is a perspective view of a third embodiment of the invention;
FIG. 14 is a top plan view of the grommet of FIG. 13;
FIG. 15 is a bottom plan view of the grommet of FIG. 13;
FIG. 16 is a first end elevation view of the grommet of FIG. 13;
FIG. 17 is a second end elevation view of the grommet of FIG. 13;
FIG. 18 is a side elevation view of the grommet of FIG. 13, the other side being a mirror image;

FIG. 19 is a perspective view of a fourth embodiment of the invention;

FIG. 20 is a top plan view of the grommet of FIG. 19;
FIG. 21 is a bottom plan view of the grommet of FIG. 19;
FIG. 22 is a first end elevation view of the grommet of FIG. 19;
FIG. 23 is a second end elevation of the grommet of FIG. 19; and,
FIG. 24 is a side elevation view of the grommet of FIG. 19; the other side being a mirror image.

The broken lines are intended to show environmental structure and form no part of the claimed design.
